[57] CLAIM

The ornamental design for my set of pocket organizers for a portfolio, as shown and described.

DESCRIPTION

FIG. 1 is a top perspective view of a set of pocket organizers for a portfolio showing my new design, the undislosed sides being flat and plain; and,

FIG. 2 is a top plan view thereof.

The broken lines shown in FIGS. 1 and 2 are for illustrative purposes only and form no part of the claimed design.
